UNITED STATES PATENT OFFICE.

MALVIN LICHTER, OF NEW YORK, N. Y.

DISPLAY-CARD.

No. 895,775.

Specification of Letters Patent.

Patented Aug. 11, 1908.

Application filed April 5, 1905. Serial No. 253,913.

To all whom it may concern:

Be it known that I, MALVIN LICHTER, a citizen of the United States, residing at New York, in the county and State of New York, have invented certain new and useful Improvements in Display-Cards, of which the following is a specification.

Figure 1 is a face view of the display card with a comb attached; Fig. 2 a face view of the card; and Fig. 3 a similar view of a slightly different form of card.

My invention relates to display cards which are provided with means for attaching combs and similar articles so that said articles may be displayed in an attractive manner.

The main object of the invention is to provide a display card to which the articles to be exhibited may be readily attached and from which the same may be readily detached, the means for attaching said articles being integral retaining strips of peculiar shape, whereby, when the article to be secured is inserted under said strips the body 25 of the card will not be distorted.

A further object of the invention is to so construct the retaining strips that they will be longer than a straight line drawn between the two points of connection between said retaining strip and the bottom, the object of which will appear hereinafter.

Another object of the invention is to so shape the retaining strip that it will tend to bend on a line oblique with respect to the body of the strip, said oblique line being substantially on a straight line between the points of attachment of the strip to the body of the card, whereby the strip will have a tendency to return to its normal position and thereby exert a slight clamping or retaining pressure on the article between the strip and the body of the card.

Referring to the various parts by numerals, 1 designates the body of the card and 2 the retaining strips. As shown in the drawing each retaining strip consists of the longitudinal member 3 and the transverse member 4, said members uniting to form a right angled retaining strip whose ends are integral with the body of the card.

The article to be attached to the card is passed under this retaining strip parallel with the inner shorter side of one arm or member of the strip, that is, as near the free point 5 of the strip as possible. When the strip is raised above the card by the article which is

to be attached to the card the tendency of the strip will be to bend at its ends on a diagonal line running through the two outside points of attachment of the strip to the body 6 of the card as indicated by the dotted lines *a* in Fig. 2. It will be noted that this will cause a slight twisting of the strip at its ends thereby giving more or less spring to said strip, it being obvious that when said strip is 6 so bent it will always tend to return to its normal position within the plane of the body of the card. It is also to be observed that the retaining strip is longer than a straight line between the points of attachment of the two ends of the strip to the body of the card, and that, therefore, said strip may be bent upward and away from the body of the card without in the least distorting the card.

As the retaining strip will swing away from the body of the card, bending on the straight line extending between the two outside points of attachment of the strip to the body of the card, as indicated by the dotted lines *a* in Fig. 2, the points 5 will move the greatest distance away from the body of the card and the device to be attached to the card can more readily be slipped under the retaining strip near said free point. It will, therefore, be seen that I not only provide a retaining strip which may be bent up or away from the body of the card without in the least distorting it, but which will exert a retaining pressure on said article to hold it under the retaining strip.

The peculiar form of retaining strip is particularly adapted for use in securing combs to cards and more especially for securing the large back combs and side combs so universally used by ladies in dressing their hair. As shown in Fig. 1, when used for this purpose, two retaining strips are arranged at suitable distance apart to receive the guard teeth 6 of the comb. These guard teeth are passed under the strips, their inner edges being arranged close to the outside edges of the longitudinally extending members of the strips, as clearly shown in said figure. It will be noted that by this arrangement the comb is prevented from moving laterally on the card, the longitudinal members of the strip serving as stops to prevent such lateral movement. By this arrangement the guard teeth are passed under the most available part of the retaining strip, that is, that part which is furthest removed from the main body of the card, so that all danger of marring or breaking

ing the retaining strips at their points of connection with the body of the card is avoided.

From the foregoing it will be obvious that my peculiar shaped retaining strip has three important functions, first, it provides a strip which is longer than the distance on a straight line between the two points of attachment of the strip to the card, so that said strip may be lifted or bent away from the card without in 10 the least distorting it; second, the strip has a tendency to return to its normal position within the plane of the card, and, therefore, exerts a retaining pressure on the article to be held; and when two of these strips are used to retain one article in position, said strips may be so placed with respect to each other that the corresponding arms of said strips will act as stops to prevent any lateral movement or displacement of the article held by them.

The advantages of a display card provided with this form of retaining strip over the old form of card having a retaining strip formed by two parallel slits or cuts in the card are obvious. As shown in Fig. 3, the strip 7 is equal in length to the distance on a straight line between the two points of attachment of the strip and the body of the card. The result of this is that when any article is forced under said strip the strip is bent upward or away from the body of the card and the card is necessarily bent inward or downward away from the strip. This is necessarily so unless, of course, the strip 7 be of elastic material. It is this bending of the body of the card which distorts it and makes it impossible to attach articles to the bottom of boxes in this manner without seriously distorting the box. The present invention is designed particularly for use in attaching articles to the inside surface of the bottom of a display box where it is necessary that the box shall not be distorted.

It is one of the important features of the invention to arrange the arms of the strips in such manner that the line of the bend of

said arms when an article is passed under them shall be oblique with respect to the sides of the strip.

Having thus described my invention, what I claim as new and desire to secure by Letters Patent, is:—

1. The combination of a display card provided with two retaining strips each adapted to be engaged by the article to be secured to said card, each strip being formed of two arms disposed at right angles, the ends of said arms being integral with the body of the card and the angle of the strip being free from the card, said strip being adapted to be bent on a line at an oblique angle to the two arms, one arm of one strip being parallel with the corresponding arm of the other strip and the other arms of said strips being in alignment, and a comb having its outer teeth substantially parallel with the parallel members of the arms and engaged under the arms that are in alignment and engaging the face of the display card.

2. In a display card the combination of a card having formed therein two retaining strips adapted to be engaged by the end teeth of a comb, each of said strips being longer than the distance on a straight line between the two ends of said strip and being adapted to bend on a line oblique to the sides of said strip, the adjoining portions of said strips being parallel with each other and a comb engaging said strips, the engaged teeth being substantially parallel with the parallel portions of the strips, whereby the comb will be detachably connected to the card without distorting the card.

In testimony whereof, I have signed my name to this specification in the presence of two subscribing witnesses, this 3d day of April 1905.

MALVIN LICHTER.
